UNITED STATES PATENT OFFICE

CARL PALMER PARK, OF MANCHESTER, NEW HAMPSHIRE, ASSIGNOR TO U. S. BOBBIN & SHUTTLE COMPANY 1929, OF PROVIDENCE, RHODE ISLAND, A CORPORATION OF RHODE ISLAND

MULTIPLE BIT BORING MACHINE WITH RECIPROCATING HEADS

Application filed January 15, 1931. Serial No. 508,949.

This invention relates to multiple bit or multiple spindle boring machines especially adapted for boring wood.

Its particular use is to bore a plurality of straight, clean, parallel holes in certain types of wooden barrels for spools used in the textile industry and particularly for those used in winding silk and rayon.

It is especially useful in the process of assembling spools for steaming yarn, especially silk yarn, of the type the same or similar to those shown in patent to Bray, #1,654,525 on steam bobbins patented January 3, 1928.

The barrels of such spools have a central hole and a plurality of other holes all of which are reënforced or lined with metal tubes. These tubes are afterwards bored with a plurality of radial holes whereby steam can enter through the ends or through these latter or vice versa.

The particular novel feature of this machine is the arrangement whereby oppositely disposed conical chucks are caused to seize and center the blank barrel after which oppositely disposed bits or other boring tools are advanced with their respective heads until the tips of the bits are perhaps one quarter of an inch from each other whereupon one set is caused to continue in the advance while the other set recedes keeping, however, at the same distance from the other set of bits.

Preferably this is all accomplished by a continuous movement of a handle which, as shown, is manually operated.

It is obvious, however, that this handle could be operated by power, if desired.

In the drawings, Fig. 1 is a front elevation.

Fig. 2 is a plan view with the blank carrier thrown back.

Fig. 3 is an enlarged plan view with the blank carrier in place holding a blank.

Fig. 4 is a vertical sectional detail of the chuck jaws holding a blank.

Fig. 4A is an elevation from the left of Fig. 4 and Fig. 4B is an elevation from the right.

Fig. 4C is a cross sectional view showing the inside of one of the driving heads.

Figs. 5, 6 and 7 are enlarged plan views

partly in section showing the different positions of the parts in the operation of the machine.

In the drawings, A represents the frame which, as shown, is supported centrally as by a column 6.

Two sets of arms 7, 7, and 8, 8, are rigidly carried by brackets 3, 3 and 2, 2 fixed to the part 1 of frame A and these pairs of arms respectively support the motor and track supports 46 and 56.

The motors 17 and 18, shown as of the electric type and as driven by wires in conduits 19 and 119 are carried by supports 46 and 56 and parallel tracks B, B, extend between them. Other types of motors or driving means might be used in place of electric.

H¹ represents a fixed holder and H² a movable holder slidable between the tracks B, B. Ordinarily movable holder H² is drawn towards the fixed holder H¹ as by tension springs 20 and 21.

Through holders H¹ and H² are the operating rod holes 22, 23, 24 and 25 through which the operating rods R¹ and R² are slidable.

The chucks C¹ and C² are carried centrally by holders H¹ and H², each chuck being of the conical type and each having four holes such as 31, 32, 33, 34 and 131, 132, 133, 134 in position opposite to each other.

D¹ and D² represent multiple bit heads partly supported by and slidable respectively with travellers 40 and 50 which are slidable along the head guide tracks B, B and really form part of each head respectively. These heads are shown as having cylindrical barrels 45 and 55 which slide in and out of the fixed supports 46 and 56.

The heads are so constructed inside that a set of boring bits 41, 42, 43, 44 or 51, 52, 53, 54 are revolved at high speed and at the same time the head can slide back and forth along the head guide tracks B, B when caused so to do as by the action of the links L and M to be described.

It is not deemed necessary to describe the interior construction of these heads as they are of a well known type.

K is a handle attached to a turn table 70

which serves as a pivot being revoluble horizontally on frame A.

This turn table 70 may be considered as all part of the handle K as it may be replaced by any other mechanism or device for operating the links L and M.

L is a rigid link pivoted at 72 to turn table 70 in a position which makes it in effect pivoted to a short arm extension of handle K beyond the center of movement. Its other end 74 is pivoted to the head D¹.

The link M is of the extensible type and includes the telescoping members 84 and 85 including a spring 86 inside the outer member 84 which tends to force the male member 85 inward.

This link M is pivoted at 82 to turn table 70 in a position which makes it substantially pivoted to the long arm of handle K or on the opposite side of the pivot from link L.

The other end of the extensible link M is pivoted to the head D² at 184.

The operating rods R¹ and R² are adjustably attached to the head D² as by being screwed into place and held in position by check nuts 60 and 61 against traveller 40.

They extend respectively through the holes 22, 23 and 24, 25 in holders H¹ and H² which serve as guides.

T is a cradle pivoted at 90 to and slideable on rod 91 between brackets 92, 92 fastened to one of the tracks B in such a manner that it can be thrown back out of the way, as shown in Fig. 2.

This cradle T, as shown in Fig. 2, has a handle 93 by which it can be lifted and is curved at 94 in such a way that when a blank barrel, such as P, is dropped into it, it will rest between the chucks C¹ and C² in such a position that when they are moved together or when C² is moved towards C¹, the end 96 of H² will engage 90 and carry T with it and blank will be picked up and centered.

The arrangement of the bits and their guide holes shown includes center bits 41 and 51 and surrounding bits 42, 43, 44 and 52, 53, 54 all those on head D¹ being arranged as nearly opposite those on D² as is possible and the guide holes in the holders H¹ and H² being also arranged in suitable alignment.

The operation is as follows:

The off position is shown in Fig. 2 where the handle is over at the extreme left and cradle T is thrown back.

When moved to the off position, the end 96 of H² engages collar 95 on rod 91 and moves cradle T over to the left.

In this position adjustable collars F¹ and F² on operating rods R¹ and R² force the holder H² with its chuck C² away from the holder H¹ and the chuck C¹.

The cradle T is thrown over between the tracks and a blank P is dropped into it.

Handle K is moved to the right which allows chuck C² to move up towards C¹ and

this lifts and centers the blank P and thereafter holds it firmly in place.

The handle is moved along more to the right, as shown in Fig. 5, and the bits enter the material from each side continuing as far 70 as the position shown in Fig. 6 where their tips may be one quarter of an inch apart.

Up to this point the two links L and M have acted together and the two heads D¹ and D² have moved at the same speed towards 75 each other.

At this time in the motion, the tips 68 and 69 of the operating rods R¹ and R² strike the head D¹ and prevent further movement of the heads D¹ and D² towards each other, but as 80 the movement of the handle continues still further to the right, as shown in Fig. 7, the link L carries the head D¹ to the left and the rods R¹ and R² force the head D² to the left, thus extending link M.

This causes the bits 41, 42, 43, 44 to retract and the bits 51, 52, 53, 54 to cut through the intervening space and also to run up into the holes which the other bits 41, 42, 43, 44 have already bored, as shown by comparing Fig. 6 90 with Fig. 7.

While the multiple bit heads D² and D¹ are of well known construction and well known articles of commerce, they must be slideable at the same time that the bits revolve.

As typical of the construction see Fig. 4C in which a central gear 101 carries a bit 41 and is itself carried by a shaft not shown which can slide in and out as from the head D² to the motor 17.

The gears 102, 103 and 104 are driven by 101 and each carries a bit such as 42, 43 and 44.

I claim:

1. In a multiple bit boring machine, the combination of a frame having head guide tracks; two chuck holders one being movable towards and from the other parallel with said tracks, and tension springs between said chuck holders; two conical chucks facing each other each chuck being carried by a holder 105 and having a plurality of aligned bit holes; two heads slideable to and from each other on the head guide tracks parallel with the holes in said chucks each head carrying a plurality of revolvable boring bits, the bits on one head pointing to and in line with those on the other head and in line with the holes in the chucks; operating rods adjustably fixed to one head and extending through the chuck holders parallel with said tracks, the free ends of said rods being in line with the other head and the rods being of a length to limit the movements of the heads towards each other; a collar on each rod in position to move the movable chuck holder away from the other; an operating handle centrally pivoted between and below the chucks, said handle having a short arm which extends beyond the pivot; an extensible link including telescoping members and a tension spring, said extensible link 115

being pivoted at one end to the long arm of the handle and at the other end to the head which carries the operating rods; and a rigid link pivoted at one end to the short arm of the handle and at the other end to the other head.

2. The combination in a multiple bit boring machine of a frame having parallel head guide tracks; of chuck holders; blank holding chucks carried by said holders each having a plurality of alined holes; with two heads slidable to and from each other on head guide tracks parallel with the holes in said chucks, each head carrying a plurality of revoluble boring bits, the bits on one head pointing to and in line with those on the other head and in line with the holes in the chucks; operating rods adjustably fixed to one head and extending parallel with said tracks; collars on said rods to move one chuck holder; a handle pivoted near one end between and below the chucks; a link pivoted at one end to the end of the handle and at the other end to a head; and an extensible link including a tension spring, said link being pivoted at one end to the handle and at the other end to the other head.

3. The combination in a multiple bit boring machine of a frame having parallel head guide tracks; and blank holding chucks positioned between the tracks each chuck having a bit passage; with two heads slidable to and from each other on the head guide tracks, each head carrying a plurality of revoluble boring bits, the bits on one head pointing to and in line with those on the other head and parallel with the tracks; operating rods adjustably fixed to one head and extending parallel with said tracks; a handle pivoted near one end between the chucks; a link pivoted at one end to one head and at the other end to the handle at one side of its pivot; and an extensible link pivoted at one end to the other head and at its other end to the handle on the other side of the handle pivot.

45 4. The combination in a boring machine of a frame having parallel head guide tracks; and blank holding chucks positioned between the tracks each chuck having a bit passage; with two heads slidable to and from each other on the head guide tracks, each head carrying a revoluble boring bit, the bit on one head pointing to and in line with that on the other head and parallel with the tracks; operating rods, adjustably fixed to one head and extending parallel with said tracks; a handle pivoted near one end between the chucks; a link pivoted at one end to one head and at the other end to the handle at one side of its pivot; and an extensible link pivoted at one end to the other head and at its other end to the handle on the other side of the handle pivot.

CARL PALMER PARK.
